SHOW-CASE DOOR.

1,094,695.

Specification of Letters Patent. Patented Apr. 28, 1914.

Application filed March 19, 1913. Serial No. 755,303.

To all whom it may concern:

Be it known that we, FOREST T. BARTON and OSCAR HENSON, citizens of the United States, residing at Seattle, in the county of King and State of Washington, have invented certain new and useful Improvements in Show-Case Doors, of which the following is a specification.

This invention relates to improvements in 10 show-cases or cabinets for exhibiting merchandise and has for its object the provision of a door of novel construction and operation whereby it may be opened and closed within a narrow space and when open is

15 wholly contained within the case.

The invention consists in the novel construction of a show-case or cabinet and the combination and adaptation therewith of devices whereby said door may be slidably 20 operated to open and close the same, as fully explained in the following specification, illustrated in the accompanying drawings, and finally set forth in the appended claims.

25 In said drawings, Figure 1 is a view partly in front elevation and partly in vertical section of a case embodying our invention. Fig. 2 is a cross sectional view through line 2—2 of Fig. 1. Fig. 3 is a fragmentary horizontal sectional view, looking upward, showing the underside of the case-top. Fig. 4 is a detached view in front elevation of a door. Figs. 5 and 6 are detached views in side elevation and top plan, 30 respectively, of details of the invention.

Referring to said drawings, the reference numeral 1 designates the base of a show-case, 2 the floor, 3 the end walls and 4 the rear wall. Said walls are desirably provided with glazed panels and support the top 5 arranged in a plane parallel with said floor. As illustrated, a pair of doors 6 and 7 are provided inclosing the front of the case and each is formed with top and bottom rails 8 and 9 and front and rear stiles 10 and 11, respectively. Vertically alined protruding pins 12 and 13 are positioned at the opposite extremities of the rear stile 11 of each door and a similar pin 14 is provided in the top rail 8 in approximately the vertical axis of the door. Each door is further provided with a channel 15 extending along its lower edge from the forward end of the lower rail 9 to a point somewhat past 45 said vertical axis of the door where said

channel terminates in a square shoulder or stop 15¹. At each end of said case a groove 16 substantially rectangular in cross-section is formed in the floor 2 extending from the proximity of the rear wall 4 parallel to and 60 adjacent the proximate side wall 3 to the forward portion of the case where it is continued in a rectangular direction, as at 17, parallel to the front edge of said floor. A similar though inverted groove 18 having 65 a corresponding rectangular portion 19 is formed in the under side of said top 5, the corresponding portions being in direct vertical alinement.

Referring to Figs. 5 and 6 which show a 70 roller support for the door, the numerals 20 and 21 designate a pair of practically similar frames pivotally connected together at 22. Pairs of rollers 23 and 24 are respectively 75 rotatably mounted in lugs 25 extending in opposite directions from said frames.

When assembled, the doors 6 and 7 are adapted to close the front opening of the show-case; the pins 12 and 14 being received within the groove 18—19 and the pin 13 in the groove 16. Of the roller support, the frame 21 is received within the groove-portion 17 and the frame 20 within the channel 15 of the door, the latter being supported upon the rollers 23. When thus assembled, 80 and the door is in closed condition, as illustrated at the right hand side of Fig. 1, the channel 15 of the door and the groove-portion 17 overlap for about the space required 85 to accommodate said roller support, the pivot 22 of which is in substantially the vertical axis of the door and in alinement with the pin 14. When thus positioned within said groove and channel with the door in closed condition, the said frames have their longitudinal axes in parallel relation and both are parallel with the horizontal axis of the door. The door is opened by pulling outwardly upon the stile 10 which causes the 90 door to swing upon its vertical axis; that is to say, upon the pivots 14 and 22, while the pins 12 and 13 are receded along the grooves 18 and 16, respectively, and causing said pin and roller support to travel longitudinally of the groove portions 17 and 19 95 toward the adjacent side wall of the case. In such transition the door will assume the position indicated by dotted lines 6¹ in Fig. 2, and the upper frame 20 of the roller support contained within the channel 15 of 100 105 110

the door will swing therewith, as indicated at 20¹ in said view, while the roller support as a whole and the pin 14 are slid in the respective groove portions 17 and 19 until 5 they reach the intersections of said groove parts with the grooves 16 and 18, whereat the door will be in the position shown in dotted lines 7¹ at the left hand side of Fig. 2. In such position, the door and the upper 10 frame 20 within the channel 15 are in alignment with the groove 16 and with a push upon the forward rail 10 of the door it is receded within the case to the position indicated by full lines at the left-hand side of 15 Fig. 2. The roller support remains fixed at the said intersection of the lower groove parts and the door is supported during such rearward movements with the minimum of friction or resistance by the rollers 23. The 20 pins 12, 13 and 14 assist in the guidance of the door rearwardly in the grooves. To close the door, the movements described are reversed; that is to say, the door is drawn outwardly upon the rollers 23 of the support 25 in directions parallel to the adjacent side wall 3 until the pin 14 is positioned at said intersection of the groove portions, then the door is swung laterally with the roller support upon the rollers 24 until the door is in 30 rectangular relation to said side wall 3.

The invention is simple in construction and operation and extremely efficient in use. There are no fixtures exposed to view, while the parts are few and not liable to get out 35 of order. While being operated the door does not project out into the adjacent aisle more than half of its length and when fully closed it is wholly contained within the case where it is compactly retained near the side 40 walls and affords unobstructed access to the interior of the cabinet.

Various modifications of our invention may obviously be made and we expressly reserve all such changes in detail within the 45 scope of the claims as may be made within the spirit of the invention and without sacrificing its advantages; for instance, the roller support may be made without the rollers, being formed of a pair of blocks 50 pivotally connected together and each member thereof filling and slidably received in the door channel 15 and the groove portion 17, respectively.

Having described our invention, what we 55 claim as new and desire to secure by Letters-Patent, is—

1. A cabinet having a floor formed with a groove consisting of two portions arranged at right angles to each other, and a 60 door formed with a channel in its lower edge communicating with said groove, and supporting means for said door positioned within said groove and channel and arranged for progressive movement in both.

65 2. A cabinet having a floor formed with

a groove, consisting of two portions arranged at right angles to each other, a top having a similarly arranged groove in its under side, and a door formed with a channel in its lower edge communicating with 70 said first named groove and provided with a plurality of guides in its upper and lower edge protruding in said grooves, one of said guides consisting in a pair of frames pivotally connected together and respectively received in said channel and said floor-groove.

3. A cabinet having a floor formed with a groove, consisting of two portions arranged at right angles to each other, a top 80 having a similarly arranged groove in its under side, and a door formed with a channel in its lower edge communicating with said first named groove and provided with a plurality of guides in its upper and lower 85 edge protruding in said grooves, one of said guides consisting in a pair of frames pivoted to each other provided with rollers respectively bearing on the bottoms of said channel and of said floor-groove. 90

4. In a cabinet of the class described, provided with a floor having a rectangular groove and a top having a similar groove in its under-face superposed in vertical alignment with said first named groove, a door 95 formed with a channel extending along its lower edge, a guide-pin in the vertical axis of said door extending into said upper groove, oppositely disposed guide pins at the rearward end of said door extending into 100 said upper and lower grooves, respectively, and a supporting member comprised of two parts pivotally connected together and respectively slidably received in said channel in said lower groove. 105

5. A cabinet having a groove in its floor extending along its front edge to the proximity of its lateral edge and thence parallel with said edge in rectangular rearward directions, and a similar superposed groove in 110 the underside of its top, in combination with a door having a channel in its lower edge communicating with and overlapping said first named groove, a plurality of devices for guiding said door along said grooves positioned respectively at opposite upper and lower rear edges of the door and in the vertical axis of the door and supporting means for the door arranged for progressive movement in said channel and said groove. 115

6. A cabinet having a groove in its floor extending along its front edge to the proximity of its lateral edge and thence parallel with said edge in rectangular rearward directions, and a similar superposed groove in 125 the underside of its top, in combination with a door having a channel in its lower edge communicating with and overlapping said first named groove, and a plurality of devices for guiding said door along said 130

grooves consisting of fixed pins positioned respectively at opposite upper and lower rear edges of the door and in the vertical axis of the door, and a supporting member 5 slidable relative to the door and retained in the said communicating channel and first named groove.

7. A cabinet having a groove in its floor extending along its front edge to the proximity of its lateral edge and thence parallel with said edge in rectangular rearward directions, and a similar superposed groove in the underside of its top, in combination with a door having a channel in its lower edge 10 communicating with and overlapping said first named groove, and a plurality of devices for guiding said door along said grooves, one of said devices consisting in a pair of frames pivotally connected together 15 and respectively received in said channel and said first named groove.

8. A cabinet having a groove in its floor extending along its front edge to the proximity of its lateral edge and thence parallel 20 with said edge in rectangular rearward directions, and a similar superposed groove in the underside of its top, in combination with a door having a channel in its lower edge communicating with and overlapping said 25 first named groove, and a plurality of devices for guiding said door along said grooves, one of said devices consisting in a pair of pivotally connected frames provided 30 with rollers respectively bearing in said 35 channel and said floor-grooves.

9. In a door structure for show cases, the

combination with upper and lower grooved tracks in the case, each having portions arranged at right angles to each other, and a door formed with a channel in its lower edge 40 communicating with said lower track, of supporting means for said door consisting in a pair of frames pivotally connected together and, respectively, slidably received in said channel and said lower track. 45

10. In a door structure for show cases, the combination with upper and lower grooved tracks in the case, each having portions arranged at right angles to each other, and a door provided with guiding means on its 50 upper and lower edges engaging in said tracks and formed with a channel in its lower edge communicating with said lower track, of supporting means for said door 55 consisting in a pair of frames pivotally connected together and, respectively, slidably received in said channel and said lower track.

11. In combination with a sliding door provided with a channel in its lower edge, 60 and a grooved track juxtaposed therewith, of a sliding support for the door consisting in a pair of frames pivoted together and adapted to be respectively received in said 65 channel and said track.

Signed at Seattle Wash., this 1st day of March, 1913.
